AIR BLAST DEVICE

Frank H. Armstrong, Chicago, Ill., assignor to
Armstrong Coalbreak Company, Benton Harbor,
Mich., a corporation of Michigan

Application October 24, 1947, Serial No. 781,940

14 Claims. (Cl. 102—25)

1

This invention relates to blasting devices, and more particularly to a device used in mining materials, such as coal, for the purpose of breaking down the coal or other material to be mined from the vein within the mine without requiring the use of explosives or of combustion.

The primary object of the invention is to provide a novel, simple, rugged device of this character which may be re-used repeatedly, and which is easy to manipulate and to adjust.

A further object is to provide a device of this character wherein the number of working parts is reduced to a minimum.

A further object is to provide a device of this character which has means for insuring an instantaneous discharge of the compressed air blast.

A further object is to provide a device of this character having a member adapted to be sheared at a given pressure which forms the control for the blast discharge, which member is provided with novel means for mounting the same in selected position.

A further object is to provide a device of this character having a pressure responsive member adapted to be shifted to blast charge releasing position upon the attainment of a predetermined pressure in a rapid manner, such member being so constructed and cooperating with the remaining parts of the device that its operation is automatically cushioned against injurious impact.

A further object is to provide a device of this character which is so constructed that it is partly disassembled in a single rapid manipulation after each use in order to condition it for reuse and in which the disassembly affords an opportunity for the user to inspect the device, to clean it, and to observe any defects, prior to each use.

A further object is to provide a device of this character in which it is impossible for air or gas at high pressure to be trapped due to breakage of internal parts.

Other objects will be apparent from the following specification.

In the drawing:

Fig. 1 is a longitudinal sectional view taken on line 1—1 of Fig. 3 and illustrating the parts in their charging position.

Fig. 2 is a longitudinal sectional view similar to Fig. 1 but illustrating the parts in their discharge or blast releasing position.

Fig. 3 is a transverse sectional view of the device taken on line 3—3 of Fig. 1.

Referring to the drawing, the numeral 10 designates a tubular body member which is formed of a diameter to fit freely and slidably within a bore hole open at the working face of the coal to be broken down by the device and which is elongated in length; for example, the length of the tube may be in the order of 50 inches although this dimension is given as illustrative only and is not

2

limiting. The tube 10 is formed of a strength to withstand pressures considerably in excess of the desired blasting pressure. Thus, if the blasting pressure is to be in the order of 10,000 pounds per square inch, the tube will be of a strength to withstand pressures of 15,000 pounds per square inch or more. The opposite ends of the tube preferably have reduced neck portions 11 which are externally screw-threaded.

- 10 An end cap 12 is provided with an internally screw-threaded skirt 13 at one end thereof which has a threaded connection with the neck 11 at one end of the tubular body 10. The end cap 12 is preferably provided with a central socket 14 at its outer end which receives a plug or fitting 15 having a neck 16 which is screw-threaded in a central bore in the end cap 12. The plug 15 preferably has a central passage 17 extending therethrough with which a conduit 18 communicates.
- 15 The outer end of the plug 15 preferably has a screw-threaded central recess therein configured to provide a support for a flared inner end portion of the conduit 18 which is wedged and clamped in pressure sealing relation by a fitting 19 screw-threaded in the socket of the fitting 15 and presses against the conduit end. The transverse face of the end cap 12 adjacent to the end 11 of the body is provided with an annular groove mounting a sealing member 20, such as an O ring, which is 20 pressed against the end of the body 10 incident to mounting of the cap 12 upon said body and which provides a continuous airtight pressure seal between the end cap and the body. It will be understood that the conduit 18 extends to a source of 25 gas, such as air under high pressure, which source may either be an air compressor or a tank of large volume containing air or other gas at a pressure greater than the desired blasting pressure of this device. The conduit 18 will be elongated to permit the positioning of the source of compressed air remote from the working face of the coal or other material to be broken down, for purposes of safety.

The end of the body 10 opposite that which 30 mounts the end cap 12 mounts a rigid cup-shaped head 25. The open end of the head 25 has a skirt 26 which is internally screw-threaded upon the adjacent neck 11 of the body, the threads 27 preferably having a fast lead to permit rapid application of the head 25 to the body 10 and rapid removal of the head from the body 10. The head 25 is provided with an interior stepped or shouldered configuration adjacent to the skirt 26, the same being provided for the purpose of receiving a bearing ring 28 and a shear ring 29. The shear ring 29 may be formed of fiber or thin mild steel or of any other material and is characterized by an inner diameter which is less than the inner diameter of the neck 11 of the body 10 adjacent thereto. The ring 28 is preferably fixedly mounted in the head 25, and the shear ring 29 is loose-

ly removably mounted for ready insertion and replacement. A circumferential groove is formed in the end of the body 10 facing head 25 and receives an annular sealing member 30, such as an O ring. An effective seal is provided between the parts when the head 25 is threaded upon the tubular body 10 by the pressure exerted by the head against the rings 28 and 29, which is in turn transmitted against the O ring 30.

The inner diameter of the portion 31 of the bore of the head leading from the skirt 26 is preferably of a dimension slightly greater than the inner diameter of the neck portion 11 adjacent thereto. A plurality of radial discharge outlets 32 are formed in the head 25 with their axes preferably inclined to both the axis of the head and the perpendicular to that axis, as illustrated. The openings 32 communicate with the portion 31 of the bore intermediate the length thereof. At its inner end the portion 33 of the bore is of a reduced or lesser diameter and forms with the end wall 34 a terminal cavity 35. A shoulder 36 is formed between bore portions 31 and 33, and a scraper or wiper ring 37, whose inner diameter is preferably the same or slightly less than the diameter 33 of the chamber 35, bears against said shoulder. A plurality of retainers 38 are carried by the head and project into the chamber defined by the bore portion 31 for the purpose of retaining the annular gasket member 37 in proper position bearing against said shoulder. An annular groove is formed in the interior small diameter bore portion 33 adjacent to the shoulder 36 and is adapted to receive and mount a sealing member 39, such as an O ring. The end wall 34 of the head is provided with a plug 40 projecting centrally and inwardly thereof for purposes to be described.

A plunger 45 of hollow construction and generally cylindrical shape is mounted in the device. The plunger 45 has an opening 46 positioned centrally at one end thereof, said opening being of a diameter to have a snug sliding fit around the plug 40 of the head when the parts are positioned as illustrated in Fig. 2. A somewhat larger opening 47 is provided centrally in the opposite end of the plunger 45. The outer diameter of the plunger is such that it has a snug sliding fit in the inner small diameter bore portion 33 of the head, and the plunger is preferably tapered at 48 at one end. The opposite end of the plunger is of greater diameter and has a radially outwardly projecting portion which terminates in an annular knife edge 49 adapted, in the position of the parts shown in Fig. 1, to bear against the inwardly projecting portion of the shear ring 29. The diameter of the enlarged head portion 50 of the plunger is preferably slightly greater than the inner diameter of the major portion of the neck 11, and said neck is stepped at its outer end at 51 to provide a stop preventing movement of the plunger 50 into the body 10.

It will be observed that the device may be conditioned for charging by applying a shear ring 29 in proper position in the head 25 to bear against the ring 28. The plunger 45 is then inserted into the head with its inner end positioned and centered by the reduced bore portion 33 and its outer enlarged head 50 bearing against the shear ring 29. When so assembled the head is threaded upon the body, the fast lead of the threads 27 facilitating rapid connection of the parts. The head is rotated until a firm frictional abutment is obtained between the ring 29 and the ring 28 on one side thereof and the sealing ring 30 on the other side thereof. Inasmuch as

the head 50 of the plunger bears against the shoulder 51, the tightening of the head 25 upon the body serves to cause the annular knife edge 50 of said head to bite into the shear ring 29.

5 When the parts are so positioned, an effective seal of the outlet 32 is provided at one end of the plunger 45 by the shear ring and its cooperating sealing ring 30 and at the other end of the device by the O ring 39.

10 The device so conditioned is inserted into the bore hole and suitably tamped in place in the manner well understood in the art. The operator then retires to a safe position, and gas, such as air under high pressure, is introduced into the body 10 through the conduit 18 and the plug member 17. It will be observed that the interior of the body 10 and of the head 25 is substantially unrestricted and, therefore, a maximum volume or storage capacity for compressed air is provided. 15 The effective area of the head 50 at the left end of the plunger 45 is greater than the area of the plunger at the other end, and, consequently, in the presence of a charge of gas at a pressure above atmosphere, the plunger 45 is forced or urged toward the right, as viewed in Fig. 1. This force acts through the knife edge 49 against the shear ring 29. When the pressure of the charge reaches a predetermined point, it produces a difference between the forces acting 20 at the opposite ends of the plunger of a predetermined value sufficient to cause the knife edge 49 to shear the ring 29. This frees the plunger which may rapidly move to the Fig. 2 position, thereby opening the outlets 32 for the rapid exhaust of the blasting charge to create the desired blast action. As the plunger 45 moves to the right it is guided by the small diameter bore portion 33 and moves with the full impact or force produced by the differential pressure action upon its opposite ends until the opening 46 thereof moves around the plug 40. Thereafter continued movement of the plunger serves to compress the gas ahead or to the right of the plunger and to build up a compressed gas cushion 25 which will reach a value counterbalancing or counteracting the charge pressure within the device before the plunger is permitted to strike the end wall 34. Consequently, the plunger 45 is prevented from striking said end wall and the 30 movement of the plunger is cushioned effectively to prevent impact which would tend to injure either the plunger or the head 25.

35 The ring 37 which encircles the plunger 45 serves as a wiping member. Consequently, any dust, dirt or abrasive particles upon the outer periphery of the plunger are wiped therefrom incident to the releasing action of the plunger in advance of the engagement of the plunger surfaces with the O ring or other sealing member 39. This serves to protect the sealing member 39 and to increase the effective life thereof.

40 The plunger 45 serves to effectively seal the outlets 32, despite the clearance between said parts, by virtue of the circumferential seals effected at 45 the opposite ends of said plunger at the shear ring 29 and sealing member 30 on the one end and at the sealing ring 39 on the other end. This sealing arrangement permits the parts to be manufactured with greater tolerances than would 50 be possible in a device employing metal-to-metal fits. It will be noted also that by virtue of the provision of the knife edge 49 upon the plunger which serves to bite into the ring 29, the sealing action is not limited to a mere abutment of 55 these parts and hence is effective to seal the joint

at this point in the presence of high blasting pressures. The provision of the knife edge 49 serves the additional function of anchoring the sealing ring against lateral displacement.

One of the important advantages of the device is the fact that the head 25 may be removed easily and quickly by virtue of the fast lead of its threads 27. Consequently, when the device is to be reconditioned, the head 25 is removed from the body 10, thereby facilitating access to the plunger for inspection thereof and also permitting inspection of the sealing rings 30 and 39 and the wiping ring 37. A fractured inner peripheral section of the shear ring is then removed from the plunger, the action of removing the head having released the large diameter portion of the shear ring automatically. A new shear ring is then applied in place and the device is reassembled. These operations can be accomplished rapidly as will be apparent, so that the time required to recondition the device is small and the reconditioning operation does not require the use of special tools nor of intricate or difficult manipulations. These factors are of importance because they enable the device to be conditioned in situ in the mine rapidly and under conditions adverse to the handling of small or intricate parts.

The provision of only one working part, namely the plunger, in the device reduces wear upon the device and makes the device very simple. The use of an annular shear member, which must be sheared completely circumferentially to release the plunger, assures an instantaneous blast discharge so that the full working effect of the charge is obtained. Efficiency is further insured because of the fact that the device will not "shoot" until the pressure necessary to shear the ring 29 is reached. Another important feature of the device is that there is no danger, as has occurred in some blast devices of this type, that air or gas may be trapped in the body or shell at high pressure due to breakage of internal parts, which condition would present a problem of potential danger to operators. It will be noted that the device avoids the use of check valves and all other parts which might be subject to failure which would result in trapping of the pressure.

Another important advantage of the device is that the simplicity of the internal construction assures the greatest possible volume in the device per unit size for the storage of the charge and permits its size to be held at a minimum with respect to the desired amount of the charge.

Another advantage is the fact that the device eliminates all necessity for internal structures, such as rods to connect a valve with a control part, inasmuch as the plunger serves at the same time the following functions: valving of the outlet, pressure response to produce movement, and the shearing action to open the valve.

While the device has been described herein primarily as an air blast device, it will be understood that other gases at high pressure may be used to charge it instead of air. It will also be understood that changes in the construction may be made within the scope of the appended claims without departing from the spirit of the invention.

I claim:

1. An indestructible blasting device comprising a tubular body, means at one end of said body for introducing therein a gas under pressure, a rigid cap detachably secured to the other end of said body and having a lateral outlet, a tubular plunger adapted to span said outlet and slidably in said cap, an enlarged head on said plunger de-

fining a shoulder and providing a larger pressure responsive area at the end of the plunger facing said means than at its opposite end, and a shear ring clamped between said cap and body and encircling said plunger and engageable by said shoulder.

2. An indestructible blasting device comprising a tubular body, means at one end of said body for introducing therein a gas under pressure, a rigid cap detachably secured to the other end of said body and having a lateral outlet, a tubular plunger adapted to span said outlet and slidably in said cap, said plunger having an enlarged head defining a shoulder and providing a larger pressure responsive area at the end of the plunger facing said means than at its opposite end, and a shear ring clamped between said cap and body and encircling said plunger and engageable by said shoulder, said shoulder terminating in a peripheral cutting edge acting against said shear ring.

3. An indestructible blasting device comprising a tubular body, means at one end of said body for introducing therein a gas under pressure, a rigid cap detachably secured to the other end of said body and having a lateral outlet, a tubular plunger adapted to span said outlet and having a sliding fit in said cap, said plunger having an enlarged head defining a shoulder and providing a larger pressure responsive area at the end of the plunger facing said means than at its opposite end, and a shear ring clamped between said cap and body and encircling said plunger and engageable by said shoulder, said body having a circumferential shoulder limiting movement of said plunger toward said means.

4. An indestructible blasting device comprising a tubular body, means at one end of said body for introducing therein a gas under pressure, a rigid cap detachably secured to the other end of said body and having a lateral outlet, a tubular plunger having a sliding fit in said cap, an enlarged head on said plunger defining a shoulder and providing a larger pressure responsive area at the end of the plunger facing said means than at its opposite end, a shear ring clamped between said cap and body and encircling said plunger and engageable by said shoulder, annular sealing means between the inner end of said plunger and said cap, and a wiping member carried by said cap between said outlet and said sealing means and encircling said plunger.

5. An indestructible blasting device comprising a tubular body, means at one end of said body for introducing therein a gas under pressure, a rigid cap detachably secured to the other end of said body and having a lateral outlet, a tubular plunger forming an outlet closure and having a sliding fit in said cap, an enlarged head on said plunger defining a shoulder and providing a larger pressure responsive area at the end of the plunger facing said means than at its opposite end, a shear ring clamped between said cap and body and encircling said plunger and engageable by said shoulder, and a central internal projection at the end of said cap normally spaced from said plunger but having a snug sliding fit in the inner end of said plunger when said plunger is released for pressure responsive movement.

6. An indestructible blasting device comprising a tubular body, means at one end of said body for introducing therein a gas under pressure, a rigid cap detachably secured to the other end of said body and having a lateral outlet, a tubular plunger forming an outlet closure and having

a sliding fit in said cap, an enlarged head on said plunger defining a shoulder and providing a larger pressure responsive area at the end of the plunger facing said means than at its opposite end, a shear ring clamped between said cap and body and encircling said plunger and engageable by said shoulder, and means carried by said cap and cooperating with said plunger to define a substantially sealed gas chamber when said plunger approaches the end of said cap upon pressure responsive movement thereof.

7. A blasting device comprising a two-part separable chambered housing having a lateral outlet in one part intermediate the plane of separation of said parts and one end of said housing, means for introducing a gaseous charge under pressure at the opposite end of the housing, a shear member clamped between said parts and projecting into the housing chamber, and a pressure responsive sleeve slidably in said housing and having a severing portion normally engaging said shear member to position the sleeve to span said outlet.

8. A blasting device comprising a two-part separable chambered housing having a lateral outlet in one part intermediate the plane of separation of said parts and one end of said housing, means for introducing a gaseous charge under pressure at the opposite end of the housing, a shear ring clamped between said parts and projecting into said housing chamber, and a pressure responsive sleeve adapted to span said outlet and having a circumferential shoulder bearing against said ring and adapted to shear said ring when said housing is charged at a selected pressure.

9. A blasting device comprising a two-part separable chambered housing having a lateral outlet in one part intermediate the plane of separation of said parts and one end of said housing, means for introducing a gaseous charge under pressure at the opposite end of the housing, a shear ring clamped between said parts and projecting into said housing chamber, a pressure responsive sleeve adapted to span said outlet and having a circumferential shoulder bearing against said ring and adapted to shear said ring when said housing is charged at a selected pressure, said ring and shoulder forming a seal between said sleeve and housing at one end of said sleeve, and a seal carried by said housing and encircling the opposite end of said sleeve.

10. A blasting device comprising a two-part separable chambered housing having a lateral outlet in one part intermediate the plane of separation of said parts and one end of said housing, means for introducing a gaseous charge under pressure at the opposite end of the housing, a shear ring clamped between said parts and projecting into said housing chamber, a pressure responsive sleeve adapted to span said outlet and having a circumferential shoulder bearing against said ring and adapted to shear said ring when said housing is charged at a selected pressure, said ring and shoulder forming a seal between said sleeve and housing at one end of said sleeve, the inner wall of said housing having a groove adjacent the opposite end of said sleeve and a soft yielding O ring seated in said groove and encircling said sleeve.

11. A blasting device comprising a two-part separable chambered housing having a lateral outlet in one part intermediate the plane of separation of said parts and one end of said housing, means for introducing a gaseous charge

5 under pressure at the opposite end of the housing, a shear ring clamped between said parts and projecting into said housing chamber, a pressure responsive tube adapted to span said outlet and having a circumferential shoulder bearing against said ring and adapted to shear said ring when said housing is charged at a selected pressure, said ring and shoulder forming a seal between said tube and housing at one end of said tube, a seal carried by said housing and encircling the opposite end of said tube, and a wiping ring carried by said housing between said outlet and said seal and encircling said tube.

12. A blasting device comprising a two-part separable chambered housing having a lateral outlet in one part intermediate the plane of separation of said parts and one end of said housing, means for introducing a gaseous charge under pressure at the opposite end of the housing, a shear ring clamped between said parts and projecting into said housing chamber, a pressure responsive tube adapted to span said outlet and having a circumferential shoulder bearing against said ring and adapted to shear said ring when said housing is charged at a selected pressure, and inwardly projecting means carried by the end of said housing opposite said first means adapted to fit in said tube to define a substantially sealed annular compressed gas cushioning chamber in advance of said tube upon released pressure responsive opening movement of said tube.

13. A blasting device comprising a two-part separable chambered housing having a lateral outlet in one part intermediate the plane of separation of said parts and one end of said housing, means for introducing a gaseous charge under pressure at the opposite end of the housing, a shear ring clamped between said parts and projecting into said housing chamber, a pressure responsive slidably sleeve adapted to span said outlet and having a circumferential shoulder bearing against said ring and adapted to shear said ring when said housing is charged at a selected pressure, said sleeve having a larger pressure responsive area at the end facing said means than at its opposite end and said flange having a perimetral cutting edge engaging said shear ring.

14. An indestructible blasting device comprising a tubular body, means at one end of said body for introducing therein a gas under pressure, a rigid cap detachably secured to the other end of said body and having a lateral outlet, a tubular plunger having a sliding fit in said cap and an enlarged head defining a shoulder and providing a larger pressure responsive area at the end of the plunger facing said means than at its opposite end, a shear ring clamped between said cap and body and encircling said plunger and engageable by said shoulder, and annular sealing means between the inner end of said plunger and said cap.
